SAFETY FIRE ESCAPE

Filed March 3, 1928

UNITED STATES PATENT OFFICE

ERNEST BOCCINO, OF NEWARK, NEW JERSEY

SAFETY FIRE ESCAPE

Application filed March 3, 1928. Serial No. 258,771.

This invention relates to fire escapes as attached to dwellings and like buildings to provide means for the safe exit of persons endangered by fire therein.

In such structures it is customary to provide such an apparatus adjacent certain of the windows of the building, having platforms accessible through the windows, and to further provide means for raising the ladder portion to some distance above the ground, thus preventing surreptitious or unwarranted entrance under normal conditions.

The ladder is provided with a counterpoise slightly less in weight than the ladder and flexibly connected to it, the remainder of the weight of the ladder being supported by connections with the platforms.

One of the objects of the present invention is to provide efficient and easily releasable means to retain the ladder when in a raised position.

A further feature is in the provision of improved means for guiding and housing the counter-poise, preventing its displacement by accident or otherwise so that it will unfailingly operate.

These and other important advantages which will appear as the description proceeds, are attained by the novel construction and combination of simple parts as hereinafter described and shown in the annexed drawings, forming a material part of this disclosure, and in which:—

Figure 1 is a side elevational view of an embodiment of the invention showing its application.

Figure 2 is an enlarged sectional view taken on line 2—2 of Figure 1.

Figure 3 is a perspective view of a support element in detail.

Figure 4 is a partial plan and sectional view of a modified form of ladder support.

The wall of a building is designated in the drawings by the numeral 10, from the upper portion of which extends a bracket 11, the same rotatably supporting a grooved wheel 12.

Trained over the wheel is a chain 13 or like flexible element, its end adjacent the

building being connected to an eye fixed in a counter-poise 14, which, when the ladder is in a raised position rests in a basket 15 supported by studs 16 set in the building wall.

The upper offset ends of the basket elements have secured in them a tube 17 held in upright position near its open top by a bracket 18, the tube being of such diameter as to permit the weight 14 to pass freely therethrough.

While the tube is indicated as of circular cross section, it will be understood that any other shape may be used conformable with the weight.

The opposite, front end of the chain is attached to the center of an arcuate loop 20 having its ends engaged with the ladder sides 21, the same being provided with rungs 22, the ladder being vertically slidably closely adjacent one end of the platform securely anchored by strips 24 to the building and provided with the usual marginal enclosing fence 25 formed by upright bars and corner posts fixed at their respective ends in the platform 23 and hand rail.

In the preferred form of ladder stop a clamp member 26, preferably made of two essentially equal die formed sockets of heavy sheet metal are engaged on the outer side of the ladder and, after adjustment, clamped by screws 27 passing through the forwardly extending wing portions 28 of the clamps.

Journalled between the lower front corners of the wings 28 is a roll 29, its periphery engaging just slightly over the corner of a strip 30 which, together with a similar strip is fixed to the platform to rigidly support a guard bar 31, these elements acting to guide the ladder in raising and lowering it, but permitting it to be moved limitedly edgewise.

It will be understood from the foregoing that if the ladder be pressed forcibly towards the wall, the roll 29 will ride up and across the strip 30 and after passing the same the ladder may be easily moved down to rest upon the ground, the weight 14 rising correspondingly.

In order to avoid inadvertent movement of the ladder by children or careless persons there may be pivoted to the back of the clamp 26, as at 32, a dog 33 having a down-reaching end to engage normally on the bar 31, as best seen in Figure 2.

The opposite end 34 of the dog is bevelled to engage in a correspondingly shaped recess in the lower end 35 of an upright lever, 10 pivoted at 36 to one of the clamp elements and having an offset portion 37 terminating in a handle 38 near the top railing of the enclosure, in position to be conveniently grasped.

15 When the lever is swung forward the dog will be released from its latch-like engagement and, turning on the pivot 32 allow the ladder to be lowered.

An additional securing means is disclosed 20 in Figure 1, the same consisting of a bracket 40 on the enclosure rail, the same frictionally housing a bar 41 having at its outer end an upturned handle 42 and at its inner end a hook 43 adapted to engage below one 25 of the rungs 22 of the latter, thereby to sustain it when raised, release taking place by turning the handle 42 into a horizontal position.

In the modification shown in Figure 4, a 30 support 45 is riveted to the platform frame 23 and mounted slidably on the support is a detent 46 having an angularly turned operating end 47 and containing an elongated slot 48 movable on headed pins 49 set in 35 the support 45, the forward end of the detent terminating in a plunger 50 adapted to enter an appropriate opening in the adjacent side 21 of the ladder.

It is to be understood that any or all of 40 the several safety devices may be used either singly or in combination as may be desired, each being effective and simple in construction and operation.

Although I have described my improvements with considerable detail and with respect to certain particular forms of my invention, I do not desire to be limited to such details since many changes and modifications may well be made without departing 50 from the spirit and scope of my invention in its broadest aspect.

Having thus described my invention, what I claim as new and desire to secure by Letters Patent, is:—

55 1. In a fire escape for buildings having a platform, a ladder serving the platform movable vertically with respect thereto, a partial counter-poise for the ladder, a clamp adjustable on the ladder, said clamp having a roll, and a strip on the platform engaging said roll and over which it may be passed to release the ladder.

60 2. In a fire escape for buildings having a platform, a ladder movable vertically relative thereto, a clamp adjustably engaged to

one side of the ladder, a roll carried by the clamp, and a support on said platform for said roll over which the clamp may be pressed by lateral force exerted on the ladder thereby to be freed of said support.

70 3. In a fire escape for buildings having a platform, a ladder movable vertically relative thereto, a counterweight partially supporting said ladder, a clamp adjustably fixed on one of the ladder sides, a roll pivoted in said clamp, a support on said platform for the roll to carry the remainder of the weight of said ladder, said roll and ladder being displaceable from the support by lateral pressure, and releasable means carried by 80 said clamp to prevent downward movement of the ladder.

75 4. In a fire escape for buildings having a platform, a ladder movable vertically relative thereto, a counterweight partially supporting said ladder, a clamp adjustably fixed on one of the ladder sides, a roll pivoted in said clamp, a support on said platform for the roll to carry the remainder of the weight of said ladder, said roll and ladder being displaceable from the support by lateral pressure, a dog pivoted on said clamp normally engageable with said support, and a hand operated lever pivoted on said clamp to release the dog.

85 5. In a fire escape for buildings having a platform, a ladder movable vertically relative thereto, a counterweight partially supporting said ladder, a clamp adjustably fixed on one of the ladder sides, a roll pivoted in said clamp, a support on said platform for the roll to carry the remainder of the weight of said ladder, said roll and ladder being displaceable from the support by lateral pressure, and a turn bolt pivoted on the 100 frame of said platform to control the movement of said ladder.

105 6. In a fire escape for buildings having a platform, a ladder movable vertically relative thereto, a counterweight partially supporting said ladder, a clamp adjustably fixed on one of the ladder sides, a roll pivoted in said clamp, a support on said platform for the roll to carry the remainder of the weight of said ladder, said roll and ladder being displaceable from the support by lateral pressure, and a turn bolt pivoted on the platform frame having an operating handle, and a hook on said bolt engageable with a 110 rung in said ladder.

115 7. In a fire escape for buildings having a platform, a ladder movable vertically relative thereto, a counterweight partially supporting said ladder, a clamp adjustably fixed on one of the ladder sides, a roll pivoted in said clamp, a support on said platform for the roll to carry the remainder of the weight of said ladder, said roll and ladder being displaceable from the support by lateral pressure, a dog pivoted on said clamp nor- 120
